RECORDING DEVICE FOR TELEPHONE SETS

Friedrich Bonn, Surth, near Cologne, Germany

Application December 5, 1936, Serial No. 114,299
In Germany August 2, 1935

2 Claims. (Cl. 234—33.5)

This invention relates to a device which is intended to be used in combination with automatic telephone sets having impulse transmitters of the dial type, for automatically recording the numbers or digits which have been set, by means of a mechanism which is mounted on the base of the telephone set on top of the rotary finger dial and coupled with the dial.

The devices hitherto suggested for this purpose, and having a recording device mounted beside or beneath the set are not sufficiently reliable in commercial use and, so far as I have observed, partly require constructional changes in the telephone sets and therefore do not meet the practical requirements.

According to one known construction, the mechanism for recording the numbers which have been dialed is accommodated in a casing which is arranged co-axially to the dial of the telephone set.

However, this device is also unsatisfactory inasmuch as the whole casing has to be turned when operating the dial plate and very complicated constructional means are required for supporting the type printing device within the rotary casing in a stationary position, covering the rotatable dial of the telephone set. Moreover, the printing of the numbers which have been set has to be effected while the dial returns to its normal position. Hence the driving power of the spring mechanism which has to accelerate the whole rotating unit and at the same time has to actuate the printing device, must be rather considerable.

Consequently the operating force which in the setting operation serves for accelerating the movable masses which are rather considerable and furthermore for winding up the spring mechanism has to be relatively great. Of course, this is a disadvantage of the known apparatus.

It is the object of the invention to obviate these drawbacks of the known recording devices. To this end, a numeral type wheel is connected to the shaft on which the additional dial is mounted, in such manner that it participates in the rotation of the shaft as the additional dial is wound up, while the numeral type wheel is locked by a mechanism when the dial starts turning back and is released by the mechanism for returning into its normal position shortly before the dial has reached normal position and after the dialed number or digit has been printed on the recording strip.

Hence, my new device has a stationary rather than a rotating casing and moreover it effects the printing at a later instant, namely shortly

before the dial has returned to normal and independent of the power which returns the dial to normal.

It will be understood that in this case it is not necessary to derive the power required for the printing from the return-spring but the momentum of returning masses in which previously energy had been stored may be utilized for the printing.

The duration of the individual telephone calls may be recorded on the recording paper strip in a simple manner by causing the paper strip with the aid of a clock-work to move at a constant speed independently from the printing action past a recording stylus or pencil as long as the set is in use.

For a complete understanding of my invention the following detailed description should be read in connection with the accompanying drawings in which

Fig. 1 is a front elevation of a telephone set, having mounted on it a recording device according to the invention;

Fig. 2 is a side elevation of the set shown in Fig. 1;

Fig. 3 is a longitudinal section of the recording device on line 3—3 in Fig. 1;

Fig. 4 shows, in larger scale and in front elevation, the printing device in its normal position;

Fig. 5 shows the same front elevation, shortly prior to the releasing of the printing device;

Fig. 6 shows diagrammatically the arrangement of the paper strip in the printing device, and the device for marking the duration of the calls; and

Fig. 7 shows the ribbon guides and the device for moving the ribbon.

The recording device is enclosed in a casing 76 which may be fastened to the supporting plate 2 by any suitable means not shown in detail, since such attaching means are immaterial so far as the present invention is concerned. The plate 2 is attached to the telephone set by means of a clamping frame 1 which corresponds in its form to the shape of the base of the telephone set.

By means of a wall or partition 3 the casing 76 is divided into two superposed compartments A and B. Rotatably mounted in the partition 3 is the center or main shaft 10 carrying at its inward end a lever 9 offset away from wall 3 so that by means of its projecting finger or stud 11 it engages the 0-hole of the dial 8 of the telephone set. The outwardly projecting end of the shaft 10 has fixed to it the dial 12. Hence the two dials 12 and 8 are mechanically coupled with

20

45

55

one another. This dial 12 is under the influence of a torsion spring 12^a housed in the protruding central portion 12^b of casing 16 and connected between a fixed point 76^a of casing 16 and shaft 10. This spring, while not absolutely necessary for the operation of the device (which could be operated alone by the telephone dial spring, not shown here), is advisable to use as an auxiliary, so as not to overload the telephone dial spring. 5

10. Mounted on the shaft 10, within the compartment B, is the control disc 13 having a partially curved recess 14 and a release pin 15 (Fig. 4). The control disc 13 is shown in its normal position and the straight edge of its recess 14 engages the projecting portion 17 of the bell crank 16 which is pivotally mounted at 16a and acted upon by the spring 16b. The free end 18 of bell crank 16 swings in the path of movement of the arm 21 of a release lever 20 pivotally mounted at 20^a and under the influence of a spring 20^b. Another branch 22 of the lever 20 lies in the path of movement of the pin 15. Secured to bell crank 16 at 23 is the printing member or type lever 24 having a little hammer 25 of rubber placed oppositely to a number type wheel 26 presenting the numerals 1, 2, 3, etc. In one rotational direction the number type roller 26 is positively coupled with the dial-carrying shaft 10 and thus with the dial 12, by means of the gears 28, 29 and 30 while in the opposite rotational direction a resilient coupling such as torsion spring 26^a is interposed between the toothed wheel 30 and the numeral type wheel 26 thus permitting the dial 12 to return to normal although the numeral type wheel 26 is prevented from rotating. To this end a locking mechanism is provided consisting of a ratchet wheel 31 having ratchet teeth 32 and being rigidly connected to the number type wheel 26, and a pawl 33 which is pivotally mounted on the lever 20. Under the action of the tension spring 35, one end of which is fast to the arm 21 of the lever 20 and the other end of which is fast to the pawl 33, the pawl 33 having at its free end a tooth 37 adapted for engagement with the ratchet wheel 31 is held against a stop 38 of lever 20.

50. Rotatably mounted on the stud 47 is the paper drum 46. Under the action of the driving roller 54 having a roughened or toothed surface frictionally engaging the paper strip, the strip 48 is unwound from the roller 46, thence it runs over the guiding members 49, 50, 51, 52, 53 and is wound up on the winding drum 55. The winding drum 55 is mounted on the plate 56 which is slidable in the direction indicated by the arrow and acted upon by a spring 56^a in such manner that drum 55 is resiliently held against the driven roller 54 and paper strip 48 lying on it, thus the paper strip 48 is prevented from slipping on the roller 54 and at the same time the roller 55 is driven in the winding direction. It will be understood that the roller 55 including its slidable mounting plate 56 is gradually displaced in the direction of the arrow, for accommodating the distance between the centers of the rollers 54 and 55 to the amount of paper wound up on the roller 55. Furthermore, by means of the upwardly bent free end 57 of the plate 56 it is possible to move the roller 55 back from the driving roller 54 as indicated by the arrow in order to render it possible to take the roller 55 with the paper reel off from the plate 56 (Fig. 6).

70. In order that the printed numerals of the call number or digit may be typed with the proper spacing on the paper strip in the dialing opera-

tion, a shifting mechanism is provided for the driving roller 54. To this end bell crank 16 has pivotally mounted at the end of its arm 58 a pawl 59, which coacts with the ratchet teeth 60 provided on the rim of the driving roller 54 and moves these teeth 60 in a clockwise direction a step sufficient so that the numerals of the dialed call number are typed with the proper spacing in a successive order on the paper strip so as to be easily readable (Figs. 4 and 5). 10

15. The paper strip 48 is besides continuously moved for the duration of a call, in order to record the duration of the call by means of a clock-work of any suitable conventional construction (not shown) which is accommodated in the compartment A. This clock-work may be of any well known type and therefore is not specifically illustrated in the drawings. The clock-work drives the driving roller 54 so as to wind up the paper strip on the winding roller 55. The paper 20 feed or drive by means of this clock-work is automatically started when the subscriber lifts the receiver from its forked cradle 11 through the medium of the arm 18 fastened to the cradle and engaging, with its forked end 19 the pivoted lever 42 which in turn, with its pin 41 may engage any suitable element of the clock-work by which it is arrested when the receiver is hung up while it is released when lifting the receiver. These auxiliary features are not shown in the drawings 30 since they are immaterial for the present invention and its understanding.

35. The mechanism for recording on the paper strip the start and end of a call consists of a lever 38 (Fig. 6) pivoted at 39 and held against the pin 41 of the lever 42, under the action of the spring 40. The lever 42 is connected with the cradle 11, in the manner described above. When the receiver is hung up, the lever 42 is so positioned that the pin 41 is in a position above the nose 43 of the lever 38. When the receiver is lifted, the lever 42 moves into the position indicated in dotted lines in Fig. 6, i. e., beneath the nose 43. By this movement the pin 41 presses against the nose 43 and causes the lever 38 to swing in counter-clockwise direction and to engage the angle piece 44 which is disposed underneath the type roller 26 the free end of the angle piece extending underneath and parallel to paper strip 48. The corresponding portion of the type roller 26 50 has been cut off in the drawings to show the angle piece 44. In the free portion of the angle piece 44 is a small hole or recess (not shown) engaged by the pin 45 when it is actuated. The paper strip 48 passes between the angle piece 44 55 and the pin 45, and each time the receiver is lifted and hung up and the lever 42 swings in counter-clockwise direction, the pin 45 makes a small hole or depression in the paper strip. It will be understood that a writing pen or pencil may also 60 be used instead of the pin 45.

65. The endless typewriter ribbon 62 (Fig. 7) runs over the ribbon roller 63, the guides 64, 65, 66 and 67 and round the type wheel 26. By the resilient member 68 connected with the guide 67 the ribbon 62 is held under slight tension. It will be understood that any other suitable means may be used for feeding the printing-ink to the type wheel such as an ink roller.

70. The ribbon 62 is moved by means of the pawl 69 pivoted under spring action on the lever 70. The lever 70 with its free end 71 engages the recess or notch of the disc 72 fixed on the dial-carrying shaft 10. Now, when the disc 72 is turned in the direction of the arrow in the 75

setting operation, the free end 71 of the lever 70 which is pivoted at 73 is lifted, the pawl 69 engages the teeth 74 of the ribbon roller 63 and moves the roller 63 including the ribbon 62.

5 In order to render it possible to make any additional notes by hand on the portion of the paper strip carrying the respective recorded call number, an aperture 75 is provided in the top wall portion of the casing, above the paper guide 51.

10 The operation of the device is as follows:

In the normal position the parts of the mechanism are in the position shown in Fig. 4. Now, when lifting the receiver, the lever 42 moves from the position shown in full lines in Fig. 4 into the 15 position shown in dotted lines, whereby the clock-work for the paper feeding mechanism is released by means of the pin 61 and permitted to operate. Simultaneously the lever 38 is swung and produces a perforation on the paper strip 48.

20 The setting of the numbers is now effected by means of the supplemental finger hold dial 12 operated in the conventional manner to operate the conventional dial 8. The rotary movement of the dial 12 is transferred to the dial 8 of the 25 telephone set by the dial-carrying shaft 16 and the lever 9. By the train of gears 28, 29, 30 the type wheel 26 is rotated accordingly in the direction indicated by the arrow in Fig. 4 so that the number or digit of the type wheel 26 corresponding with the dialed character stands opposite to the hammer 25 when each single dialing 30 operation is finished.

In the dialing operation the disc 13 is turned in the direction indicated by the arrow in Fig. 4. 35 The projection 17 of the lever 16 thereby slides along on the incline of the recess 14 and the lever 16 is lifted on its fulcrum 16a into the position Fig. 5, thus tensioning the helical spring 16b. The pawl 59 thereby rotates the paper driving roller 54 through a predetermined angle. Due to the rotary movement of the disc 13 the pin 15 disengages the lever 20 so that the latter is swung round its fulcrum 20a under the influence of spring 20b in a clockwise direction and 40 thereby its free end 21 is moved into the return path of bell crank arm 19 as shown in Fig. 5. Simultaneously the pawl 33 is also swung clockwise and its locking tooth 37 engages the ratchet teeth 32 of the wheel 31 and thereby prevents 45 this wheel from rotating clockwise.

50 Now, when the finger of the operator disengages the dial 12, it returns to normal in the usual manner under the action of spring 12a. The parts 16, 20, 33 and the type wheel 26 on the other hand are kept in their displaced position shown in Fig. 5 up to a predetermined instant shortly before the dial 12 has reached normal and when disc 13 is about to arrive, clockwise turning, in the position shown in Fig. 4. At this instant, which is shown in Fig. 5, the pin 15 contacts the lever arm 22 and lifts it into the position Fig. 4, thus releasing arm 19 of bell crank 16 and allowing its detent 17 to snap into cam recess 14 under the action of the spring 16b. The hammer 25 is thereby impelled against the type lying in front of it and the respective type is printed on the paper strip 48 by the medium of the ribbon 62. When this operation is finished, lever 22 rises slightly higher so that, as shown in Fig. 65 70, pawl 37 becomes disengaged from ratchet wheel 31 and the latter together with type wheel 26 return to normal under the action of the coupling or torsion spring 26a.

The same cycle or sequence of operations will 75 be repeated with every single dialing operation

so that the numbers or digits are successively typed or printed on the paper strip. When the receiver is hung up, the lever 42 is moved back into its normal position and acts again upon the lever 38 which in consequence thereof again 5 presses or prints a mark into or onto the paper strip. Simultaneously the spring-actuated member 61 locks the clock-work so that the movement of the paper strip 48 is stopped. From the two marks made on the paper strip 48 by the lever 10 15 20 25 30 35 40 45 50 55 60 65 70 75 80 85 90 95 100 105 110 115 120 125 130 135 140 145 150 155 160 165 170 175 180 185 190 195 200 205
